UNITED STATES PATENT OFFICE.

HENRY JIMISON GOODLETT, OF LANEVILLE, TEXAS.

HEEL-SWEEP BRACE.

1,241,958.

Specification of Letters Patent.

Patented Oct. 2, 1917.

Application filed May 18, 1917. Serial No. 169,542.

To all whom it may concern:

Be it known that I, HENRY J. GOODLETT, a citizen of the United States, residing at Laneville, in the county of Rusk and State 5 of Texas, have invented certain new and useful Improvements in Heel-Sweep Braces; and I do hereby declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 This invention relates to new and useful improvements in attachments to cultivators for strengthening the heel sweep thereof and prevent the same from rocking upon the foot.

20 The invention comprises a simple and efficient brace for this purpose having various details of construction, combinations and arrangements of parts which will be herein-after fully described, shown in the accompanying drawings and then specifically defined in the appended claim.

25 My invention is illustrated in the accompanying drawings, in which:—

Figure 1 is a rear view showing the application of my invention to a cultivator.

Fig. 2 is a detail of the brace removed from the cultivator.

Reference now being had to the details of the drawings by letter, A designates a cultivator having wings A' and mounted between the bars B, secured to the beam C in the usual manner upon cultivators of this type. My invention comprises the brace plate D which has a shank portion D' which

is curved and extends between the bars B, 40 preventing lateral movement to the brace and has an angular-outlined opening F therein. The plate proper is curved as shown to conform to the curvature of the rear faces of the wings of the cultivator and contracted portions E upon the upper part 45 of the plate are bent to form hooks E' which engage over the upper edges of the wings A', thus forming secure means for strengthening and steadyng the cultivator. A bolt 50 K passes through the aperture of the plate and is engaged by a nut N whereby the brace may be securely held to the cultivator.

By the provision of a heel sweep brace made in accordance with my invention, it 55 will be noted that, when the same is applied to the cultivator in the manner shown, the cultivator will be prevented from rocking upon the foot and the wings strengthened and held rigidly in proper position for ef- 60 fectual service.

What I claim to be new is:—

In combination with a cultivator having supporting bars, a heel sweep brace made of a curved sheet of metal and apertured, 65 projections upon the upper edge of the brace which are bent to form hooks for engagement over the upper edges of the plow, and a curved shank portion of the plate engaging between the bars which support the cultivator.

In testimony whereof I hereunto affix my signature in presence of two witnesses.

HENRY JIMISON GOODLETT.

Witnesses:

GRODY B. ROSS,
NEWELL FITE.
